AMMUNITION DISPENSER

William H. Richards, Jr., 724 E. Century Blvd., Los Angeles, Calif., and Curtis H. Shreve, 4227 Redondo Beach Blvd., Lawndale, Calif.

Filed Feb. 15, 1960, Ser. No. 59,397

Term of patent 14 years

(Cl. D52—2)

FIG. 1.

FIG. 2.

FIG. 3.

FIG. 4.

FIG. 6.

FIG. 5.

FIG. 1 is a front elevation of the ammunition dispenser embodying our new design.

FIG. 2 is a side view of the dispenser.

FIG. 3 is a rear view of the dispenser.

FIG. 4 is a top plan view of the dispenser.

FIG. 5 is a bottom view of the dispenser.

FIG. 6 is a perspective view of the dispenser taken from the front, one side and top thereof.

The essential features of the design reside in the portions shown in full lines. The lines on the periphery of the knob represent milling.

We claim:

The ornamental design for an ammunition dispenser, as shown and described.
